UNITED STATES PATENT OFFICE.

ORLANDO J. ROOT, OF EAST MOLINE, ILLINOIS.

SPARKING-DEVICE GOVERNOR FOR GASOLENE-ENGINES.

SPECIFICATION forming part of Letters Patent No. 733,752, dated July 14, 1903.

Application filed December 16, 1902. Serial No. 135,426. (No model.)

To all whom it may concern:

Be it known that I, ORLANDO J. ROOT, a citizen of the United States, residing at East Moline, in the county of Rock Island and State 5 of Illinois, have invented certain new and useful Improvements in Sparking-Device Governors for Gasolene-Engines, of which the following is a specification.

This invention relates to gasolene or vapor 10 engines, and pertains particularly to sparking devices of explosive-engines.

The prime object of this invention is to provide means for tripping and timing the sparker-igniter hammer of explosive-engines 15 from the ordinary push-rod of such engines.

A further object of the invention is to provide mechanism to hold a sparking device inoperative and to prevent sparking when an 20 engine is running idle.

A still further object of the invention is to 25 provide a break-spark mechanism combined with a governor or an automatic device to hold said mechanism against sparking except when a charge or explosion is required, whereby an engine will be prevented from 30 sparking while running idle.

As far as known to me in the form of sparkers herein shown the well-known cam-operated vertical push-rod of a sparking device 35 has only been used to push down the exhaust-valve of an engine, which is done by the raised portion of a cam of the ordinary form employed in the vertical type of engines engaging a roller carried by an arm connected 40 to the said vertical push-rod. It is my purpose to have said rod when combined with my device perform the additional function of preventing sparking during the idle running of the engine except when a charge or an explosion is required.

To this end my invention consists, first, in an adjustable trip-screw positioned adjacent a push-rod and an igniter spring-trip secured to the rod and projecting between the rod and 45 the said screw, so as to operate the sparker-igniter hammer; second, in a cam of peculiar shape, a catch-lever pivoted in relation to a roller-arm attached to a push-rod, so that an upward movement of said arm under pressure 50 of the cam on said roller will permit a dog or pawl of the catch-lever to catch under the arm and hold it to its highest elevation,

and, third, in an automatic device operated from the main shaft of the engine to throw the dog or pawl under the arm simultaneously 55 with the arm reaching its highest point of elevation.

In the accompanying drawings, forming part of this application, Figure 1 is an elevation of a vertical engine embodying my invention with one of the fly-wheels removed. Fig. 2 is a detail elevation of the igniter-hammer, exhaust-screw, trip-spring, and push-rod partly broken away. Fig. 3 is a sectional view of the parts shown in Fig. 2, taken on 60 the plane indicated by the dotted line x x . Fig. 4 is a detail inner side elevation of the balance or fly wheel carrying the device for operating the catch-lever. Fig. 5 is a detail perspective view of part of the catch-lever- 65 operating device. Fig. 6 is a perspective view of the catch-lever. Fig. 7 is an elevation of part of an engine, showing a modification. 70

The same numeral references denote the 75 same parts throughout the several views of the drawings.

The engine being of ordinary type, only such parts thereof as have connection with my invention will be herein described. 80

The push-rod 1 is operated by a cam 2 working against a roller 11, carried by a pivoted arm 3, on which the push-rod is seated, and said cam is operated by suitable interior gearing from the main shaft 1^a of the engine. 85 Heretofore the push-rod 1 has only been used to push down the exhaust-valve at the proper time by the raised portion of the cam 2 elevating the arm 3; but inasmuch as the spark is timed at the opposite end of the stroke 90 from the exhaust-valve opening I am enabled to make a double use of the push-rod—viz., the ordinary use of said rod and its use to hold the sparking device inactive. To produce this use of the push-rod, I provide it with 95 an igniter spring-trip 4, adjustably secured to the rod and preferably composed of tool-steel and having a beveled head 5, tapering from the top end of the spring downwardly and outwardly and terminating in a shoulder 100 6. The trip-plate 7 is provided with a set-screw 8, set on an incline or at an angle to the push-rod and against which the beveled head 5 works perpendicular thereto, and the

shoulder 6 is engaged by the spark-igniter hammer 9. The screw 8 is capable of adjustment so that the timing of the trip of the igniter-hammer may be varied as desired or as 5 occasion may demand.

It is obvious that the spring-trip 4 is applicable to any form of the rod used for timing the spark-igniter and that said spring-trip is stiff enough to retain its proper position 10 when raising the igniter-hammer, and yet it is flexible enough to spring past the hammer on its downward stroke. To prevent the above-noted mechanism from working except when a spark is desired, I remove a portion 15 of the cam 2 or cut it away, so as to form a flat surface 10 about opposite its highest portion, so that the cam will pass under the roller 11 without working the arm 3 when the latter is in raised position. To hold the arm 20 3 and push-rod 1 fixed in raised position, a plate 12, having a notch 13, is secured upon the under side of the arm, and a catch-lever 14 is pivoted at 15 and has a strike-plate 15^a and a dog 16 to engage the notch 13. The dog 25 is held in retracted position by a spiral spring 17, and the lever 14 is automatically operated to throw the dog under the arm 3 and into the notch 12 simultaneously with the arm reaching its highest elevation by a device 30 carried by one of the fly-wheels 18 of the engine, which device comprises a lever 19, having a shoe 20 and having one end pivoted to one of said wheel-spokes at 21 and the other end provided with a weight 22, having an ear 35 23, to which ear one end of a spiral spring 24 is attached, and the other end of said spring is adjustably secured to another of said wheel-spokes by a screw-rod 25 and nut 25^a.

Referring to the modification shown in Fig. 40 7, a notch 26 is made on the under side of the roller-arm 27, and in lieu of the spring-controlled shoe-lever hereinbefore referred to a projection or strike-plate 28 is secured to the engine-shaft to throw the catch-lever dog 45 into the notch 26.

The operation is as follows: Upon the upward stroke of the push-rod the shoulder of the spring-trip raises the hammer and is pushed therefrom by set-screw 8 engaging the 50 beveled head 5, said set-screw being adjusted so as to vary the length of time that the shoulder shall hold the hammer, and upon the downward stroke of the rod the flexibility of the trip permits it to spring over the hammer 55 without operating it. Simultaneously with the raising of the arm 3 and push-rod 1 the shoe 20 strikes the plate 15^a of the catch-lever and pushes it outwardly, which forces the dog under the arm 3 and into the plate-notch, so that the said lever catches and holds the arm and push-rod in raised position 60 and permits a continued running of the engine, with the sparking device idle, as long as the lever holds said arm up. So long as the 65 speed of the engine is normal the shoe does not operate the catch-lever; but in excessive speed of the engine the shoe is swung out-

ward against the strike-plate of said lever, which throws the dog under the arm 33, with results as hereinbefore stated. When the 70 speed of the engine has been thus reduced, the dog is retracted by the spring 17.

It will be seen that the action of the spring-trip on the trip-hammer can be varied as desired by simply adjusting the igniter set-screw so that the latter will shorten or prolong the holding of the hammer by the shoulder of the spring-trip, and thereby time the explosion as desired.

It is obvious that a very slight movement 80 of the push-rod is possible while the governor is in operation, that much wear on the parts of the sparking mechanism is avoided, and that while a continued running of the engine is not interfered with the sparking device is 85 automatically put out of action and held so by the governor.

It will be seen that the tension of the shoe-lever on the catch-lever may be varied as desired by adjusting the screw-rod of the shoe-spring and that my improved devices may be readily applied to engines of various forms.

Having thus described my invention, what I claim as new, and desire to secure by Letters Patent, is—

1. In an explosive-engine, the combination, with a spark-igniter, and a spring-trip attached to and working in unison with a push or similar engine rod to raise the hammer and having a beveled head, of a set-screw perpendicular to and engaging the beveled head to time the operation of the hammer.

2. In an explosive-engine, the combination, with a push-rod, an igniter-hammer, and a trip-plate, of a set-screw adjustable on the 105 trip-plate at an angle to the rod, and a spring-trip having one end secured to the rod and the other end having a beveled head perpendicular to and in engagement with the set-screw.

3. The combination, with a push-rod, and an igniter-hammer, of a set-screw inclined to the rod, and a spring-trip having one end secured to the rod and extending parallel with the latter and having a shoulder to work the 115 hammer, and the beveled or inclined trip-head working on the set-screw perpendicular thereto.

4. In a sparking device for explosive-engine, the combination of a spark-igniter, an igniter-trip set-screw, a spring-trip having a beveled portion perpendicular to the screw and terminating in a shoulder controlled in its action on the hammer by the set-screw, and a push-rod having said spring-trip secured thereto parallel therewith.

5. The combination, with a push-rod, an igniter-hammer, an igniter-trip, and a spring-trip carried by the rod parallel thereto and having a beveled free end terminating in a 130 shoulder to work the hammer, of a dog pivoted adjacent the main shaft of the engine and having a strike-plate, a shoe operated by said shaft to strike said plate and throw

the dog under the rod, and a spring to retract the dog.

6. In a sparking-device governor for gasoline-engines, the combination, with a push-rod, a roller-arm supporting the rod, and a cam to operate the arm and having a reduced portion, of a dog pivoted to the face of the engine and having a strike-plate, a spring-controlled lever carried by the engine fly-wheel and having a lateral shoe to engage the said plate and automatically throw the dog under the roller-arm simultaneously with the said arm reaching its highest elevation, and a spring to retract the dog.

15 7. The combination, with a gasoline-engine, having a break-spark device, a pivoted arm carrying a roller, a push-rod supported upon the arm, a cam working against the roller to raise the arm, a spring-trip secured to and

standing parallel with the push-rod and having a beveled shouldered head, and a set-screw perpendicular to the said head to control the spring movement of the trip, of a notched plate upon said arm, a dog pivoted below said plate and having a strike-plate, a 25 weighted spring-controlled lever pivoted to the engine fly-wheel, a lateral shoe on this lever between its pivoted and weighted ends, said shoe engaging the strike-plate to throw the dog into engagement with the notched 30 plate simultaneously with the raising of the roller-arm, and a spring to retract the dog.

In witness whereof I hereunto set my hand in the presence of two witnesses.
